FEED WATER HEATER FOR BOILERS

Harry A. Scott, Houston, Tex.

Application July 18, 1935, Serial No. 32,100

1 Claim. (Cl. 257—252)

This invention relates to feed water heaters for boilers, and has for the primary object the provision of a device of this character which will efficiently heat feed water for a boiler by employing waste heat and gases from the boiler and which may be readily adapted to a boiler and permit the boiler tubes to be easily cleaned and repaired and other repairs made which may be necessary to the interior of the boiler from the smoke box thereof and provides a device adaptable for boilers employed in oil fields which require frequent cleaning and repairing due to the fuel burnt therein.

With these and other objects in view, this invention consists in certain novel features of construction, combination and arrangement of parts to be hereinafter more fully described and claimed.

For a complete understanding of my invention, reference is to be had to the following description and accompanying drawings, in which—

Figure 1 is a transverse sectional view showing a boiler equipped with a feed water heater constructed in accordance with this invention.

Figure 2 is a fragmentary vertical sectional view illustrating the same and showing in dotted lines the heater positioned in an inoperative position.

Figure 3 is a fragmentary transverse sectional view drawn on an enlarged scale showing a mounting of the feed water heater in the smoke box of a boiler.

Figure 4 is a fragmentary side elevation showing the door of the smoke box in a closed position.

Referring in detail to the drawings, the numeral 1 indicates a steam boiler of a conventional construction and of a type principally employed in oil fields. The boiler has the usual boiler tubes 2, smoke box 3 and smoke stack 4. The front of the smoke box may be opened by a hinged door 5 to give access to the smoke box for the purpose of making interior repairs for the boiler.

The foregoing description briefly sets forth a boiler to which my invention is adapted.

Substantially U-shaped hangers 6 are removably secured to the upper wall of the smoke box 3 and form journals for a feed water heater 7 which in normal operation is disposed vertically in the smoke box 3 and adjacent to the discharge end of the tubes 2 so that the waste heat and gases of the boiler will act on the feed water heater 7 prior to passing to the smoke stack 4. The heater 7 has connected thereto horizontally arranged pipes 8 and 9 journaled in the hangers 6 and extend through opposite walls of the smoke

box and are connected to pipes 10 and 11 by unions 12. The pipe 9 provides the outlet for the heater and has direct connection with the boiler by a pipe 13 so that the water after passing from the heater may enter the boiler. A control valve 14 is arranged in the pipe 9. The connection between the pipe 9 and the pipe 13 is by a T-coupling 15 to which the pipe 11 is connected. The pipe 10 has a control valve 16 and the pipe 11 has a control valve 17. The pipe 10 is connected to a water supply pipe 18 by a T-coupling 19 and the latter has the pipe 11 connected thereto.

The heater 7 includes an upper head 20 and a series of lower heads 21, each of semispherical shape and each provided with a drain plug 22. The upper head 20 is divided into chambers 23, 24, 25 and 26. Connected to each lower head 21 are groups of pipes or tubes 27 and 28. The tubes 27 of the lower righthand head 21 are connected to the chamber 23 of the upper head 20 and the tubes 28 are connected to the chamber 24. The lower intermediate head has the tubes 27 thereof connected to the chamber 24 and the tubes 28 to the chamber 25. The lefthand lower head has the tubes 27 thereof connected to the chamber 25 and the tubes 28 connected to the chamber 26. The chamber 23 is the inlet chamber and the chamber 26 is the outlet chamber for the water. The tubes 27 form down passages for the water while the tubes 28 form up passages for the water. It will thus be seen that the water entering from the supply or the pipe 10 is caused to travel upwardly and downwardly several times in the heater before passing therefrom to the pipe 9 so that the temperature of the water will be gradually raised from the inlet end of the heater to the outlet end of the heater by employing the waste heat and gases from the boiler. When it is desired to clean the boiler, the unions 12 are released and the heater swung into a horizontal position, as shown in dotted lines in Figure 2, where it is supported by a bar 28' carried by a bracket 29 mounted on the boiler. The heater thus positioned will permit free access to the interior of the smoke box and the boiler tubes 2 for cleaning and repair. The entire heater may be readily removed from the smoke box by detaching the pipes 8 and 9 therefrom.

Further, it is to be noted that the operation of the boiler can be continued while the heater is in an inoperative position by closing the valves 16 and 14 and opening the valve 17.

The employment of a series of lower heads to the heater will permit the heater to readily ex-

pand and contract. As the water progresses from the inlet end of the heater to the outlet end there will be a variance in the expansion and contraction of portions of the heater and the 5 employment of the independent lower heads will readily compensate for the variance in expansion and contraction throughout the heater.

A bypass 30 connects the bottom of the boiler to the feed pipe 10 between the valve 16 and the 10 inlet pipe 8 and has located therein a check valve 31. The bypass also includes a pipe 32 which connects the boiler to the pipe 11 and has a check valve 33 therein so that should the water supply fail during the operation of the boiler, 15 the heater may have water circulation with the boiler to prevent damage to the heater from lack of water.

Having described the invention, I claim:

A heater for the purpose set forth, comprising an upper head, lower heads and tubes connected to the upper head and lower heads, water inlet and outlet pipes connected respectively to the ends of the upper head and adjustable hangers supporting said pipes, said upper head having partitions dividing the same into a plurality of closed compartments and the lower heads being substantially U-shaped in cross section and being spaced from each other and the tubes connecting 10 the upper head and lower heads being arranged in spaced series to permit the water from the inlet pipe flowing continuously in opposite directions through the several compartments in the upper head and through the spaced lower heads 15 before finding an outlet through the outlet pipe.

HARRY A. SCOTT.
